Primary Examiner — Angela J Lee(74) *Attorney, Agent, or Firm* — Mark E. Rose; Philip N. Smith(57) **CLAIM**

The ornamental design for a visual display screen with icon, as shown and described.

DESCRIPTION

The FIGURE is a front view of an icon for a portion of a visual display screen according to my new design.

The broken lines showing of the portions of the visual display screen are for the purpose of illustrating environmental structure and form no part of the claimed design.
